UNITED STATES PATENT OFFICE

171,638

HOOD ORNAMENT

Arley O. Clark, Laurel Springs, N. C.

Application July 2, 1953, Serial No. 25,765

Term of patent 7 years

(Cl. D14—18)

To all whom it may concern:

Be it known that I, Arley O. Clark, a citizen of the United States of America, residing at Laurel Springs, in the county of Alleghany and State of North Carolina, have invented a new, original, and ornamental Design for a Hood Ornament, of which the following is a specification, reference being had to the accompanying drawing, forming a part thereof.

In the drawing:

I claim:

The ornamental design for a hood ornament, as shown.

ARLEY O. CLARK.
